UNITED STATES PATENT OFFICE.

GEORGE W. PIGGOTT, OF NEW YORK, N. Y., ASSIGNOR TO HARTFORD CARPET COMPANY, OF HARTFORD, CONNECTICUT.

DESIGN FOR CARPET.

Specification forming part of Design No. **11,094**, dated March 25, 1879; application filed February 24, 1879.
[Term of patent 3½ years.]

To all whom it may concern:

Be it known that I, GEORGE W. PIGGOTT, of the city of New York, in the county and State of New York, have invented a new and original Design for a Carpet, of which the following is a specification:

This invention relates to a new and original design for carpet, oil-cloth, and similar fabrics.

It consists of the new ornamentation and arrangement of parts constituting the design, hereinafter more fully pointed out.

The accompanying photographic illustration represents a face view of my newly-invented design.

The design consists of a multitude of figures, most of which are rectangular, richly ornamented and arranged, as shown in the photographic illustration, so as to constitute one complete harmonious design.

The letter *a* represents a rectangle. At one of its shorter sides is another smaller rectangle, *b*, which interlocks with an octagon, *d*. A border extends partly around the figure *b*. *e* is another rectangle placed at the side of the figure *b*, and partly overlapped by the octagon *d*.

f g h are three L-shaped figures placed side by side. Into the angle of the figure *h* enters one corner of a six-sided figure, *i*, which is placed beneath the figure *g*. The oblique edge of the figure *i* is in contact with a five-sided figure, *j*, which is situated beneath the figure *h*. *k* is another larger L-shaped figure, whose upward extension overlaps one corner of the figure *f*. *l m n* is another group of figures, situated at one side of the figures *f k*, the L-shaped figure *l* and the rectangle *n* being bordered by the figures *f k* on one side, while the rectangle *m* is situated at the other side of the figure *l*.

o is a rectangle, which is situated beneath and partly overlaps the figure *n*. Beneath the figures *n k* is a figure, *p*, which at one corner is partly overlapped by the octagon *d*, above described. *q* is a rectangle, beneath the figures *j k*, and partly overlapped by the latter figure at one side and by the figure *m* at the other side. Beneath the rectangle *q* is another rectangle, *r*, which has a triangular extension, *s*, that borders the figure *a* above described.

All the figures constituting the above design are executed preferably in contrasting colors, many are partly surrounded by borders, and all are richly ornamented by floral and other designs.

I claim—

1. The design for a carpet, consisting of the figures *a b d*, substantially as shown.
2. The design for a carpet, consisting of the figures *f g h*, substantially as shown.
3. The design for a carpet, consisting of the figures *g h i j*, substantially as shown.
4. The design for a carpet, consisting of the figures *l m n*, substantially as shown.
5. The design for a carpet, consisting of the figures *f k i*, substantially as shown.
6. The design for a carpet, consisting of the figures *o p q r*, substantially as shown.
7. The design for a carpet, consisting of the figures *r s a*, substantially as shown.
8. The design for a carpet, consisting of the figures *a b d e f g h i j k l m n o p q r s*, substantially as shown.

GEO. W. PIGGOTT.
